UNITED STATES PATENT OFFICE.

SEBASTIAN C. HOFMANN, OF OSAGE CITY, MISSOURI, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,233,473.

Specification of Letters Patent. Patented July 17, 1917.

Application filed December 30, 1913. Serial No. 809,493.

To all whom it may concern:

Be it known that I, SEBASTIAN C. HOFMANN, a citizen of the United States, residing at Osage City, in the county of Cole 5 and State of Missouri, have invented certain new and useful Improvements in Railway Signaling, of which the following is a specification.

My invention relates to railway signaling, 10 and particularly to signaling for stretches of single track over which traffic moves in both directions, such for example, as stretches of single track between passing sidings.

I will describe certain forms of signaling system embodying my invention, and will then point out the novel features thereof in claims.

In the accompanying drawings, Figure 1 20 is a diagrammatic view showing a stretch of single track having applied thereto one form of signaling system embodying my invention, and Fig. 2 is a view showing a modification of the apparatus shown in 25 Fig. 1.

Similar reference characters refer to similar parts in both of the views.

Referring first to Fig. 1, A—B is a stretch of single track between two passing 30 sidings E and F, over which stretch traffic moves in both directions. Traffic through this stretch from east to west is governed by signals S', S³ and S⁶ located at intervals through the stretch, and traffic through the 35 stretch from west to east is governed by other signals S², S⁴ and S⁵, located also at intervals through the stretch.

Each signal comprises a semaphore 2, biased by gravity or otherwise to the danger position of indication, an electric motor 3, for moving the semaphore to another position against its bias, and a holding magnet 4 for holding the semaphore in the position to which it has been moved by the 45 motor. In my invention, the motor 3 is operatively connected with the semaphore to be driven as a generator thereby while the semaphore is returning to danger position in response to its bias. Also in my invention the armature of the holding magnet 4 controls a contact 6 in such manner that when the magnet is energized this contact engages a front contact point 7, and when the magnet is deenergized this contact 53 6 engages a back contact point 8. The

armature of magnet 4 is operatively connected with the signal mechanism in a suitable manner, this connection being indicated diagrammatically in the drawings for the sake of simplicity.

In the drawings, I have shown the parts of the signal mechanism and the circuits for signals S', S³ and S⁶ only, but it is understood that the mechanism for each of the other signals is similar to that shown for signals S', S³ and S⁶, also that the circuits for signals S² and S⁵ are similar to those for signals S⁴ and S⁸, and that the circuit for signal S² is similar to that for signal S'.

The stretch A—B is divided by insulated joints 58 into several sections A—C, C—D and D—B, and as here shown a pair of opposing signals is located near each junction of adjacent sections, although I do not wish to be limited to this particular location of the signals. Each section is provided with one or more track circuits including track relays for the control of the signals. As here shown each section is divided by insulated joints 58 into two sub-sections, and each sub-section is provided with a separate track circuit. For example, section A—C is divided into two sub-sections A—9 9—C. Each track circuit comprises the rails of the subsection, a battery b, and a track relay; 85 the track relays are designated by the reference character T with the same exponent as that of the adjacent signal which governs traffic through the corresponding sub-section.

For each signal I provide a signal relay for the control thereof, which relays are designated in the drawing by the reference character R with an exponent corresponding to the exponent of the signal which the relay controls. Each signal is provided with a circuit which is controlled by the corresponding signal relay. For example, the circuit for signal S³ is from battery 10 through wires 11, 12, 13, and 27, contact 28 of relay R³, wire 29, holding magnet 4, wire 30 and common wire 0 to battery 10. This circuit when closed energizes magnet 4 thereby closing contact 6—7 of this magnet so that the signal motor 3 is then energized by a branch of the signal circuit, which branch is from wire 29 through circuit controller 5, wire 31, contact 7—6, wire 32, motor 3, wire 33, to wire 30. Circuit controller 5 is operated by the signal mechanism and 110

opens when the signal reaches clear position so that the motor 3 then stops. Each of the other signals is provided with a circuit similar to that for signal S³.

5 Each signal relay (except relays R⁶ and R⁵) is controlled by both track relays for the section through which the corresponding signal governs traffic, and also by the signal relay for the signal next in advance governing traffic in the same direction. For example, relay R', which controls signal S', is provided with the following circuit—from battery 10, through wires 11, 12, 13 and 14, contact 15 of relay R³, wires 16 and 17, contact 18 of track relay T⁶, wire 19, contact 20 of track relay T', wire 21, signal relay R', wires 22 and 23, and common wire 0 to battery 10. The circuits for signal relays R³, R⁴, and R² are similar to that just traced for relay R'. The circuits for signal relays R⁶ and R⁵ are similar to that just traced for relay R' except that they are controlled only by the track relays for sections D—B and A—C respectively, there being, in the 25 form of signaling here shown, no signal relays to control these circuits.

It will be seen that as thus far described, each signal relay controls the signal relay for the signal next in the rear governing traffic in the same direction. Hence, as a train enters the stretch from either end, all the signals governing traffic through the stretch in the direction opposite to that in which the train is moving will change to danger indication. Means are provided, however, for each signal relay for at times rendering it ineffective to control the signal relay next in the rear, so that as a train proceeds through the stretch certain signals in the rear of the train may change to clear position thereby permitting a following train to proceed through the stretch at a safe distance from the first train. This means, as here shown, is a branch around the signal relay contact, which branch is controlled by an auxiliary relay. These auxiliary relays are in the drawing designated by the reference character X with the same exponent as that of the corresponding signal relay. 40 For example, the branch around contact 15 of signal relay R³ is from wire 11 through wire 24, contact 25 of auxiliary relay X³, wire 26, to wire 17. It will be seen that each auxiliary relay, when energized, closes the 45 branch around the contact of the corresponding signal relay and thus renders such signal relay ineffective to control the signal relay for the signal next in the rear. No auxiliary relays are provided for signal relays R' and R², because these relays do not control other signal relays in the illustrated embodiment of my invention.

In the embodiment of my invention shown in Fig. 1, each auxiliary relay X comprises 65 two windings, viz., a pick-up winding 34 and

a holding winding 35. The pick-up winding 34 of each of these relays is arranged to be energized by current generated by the motor 3 of the corresponding signal while the signal is moving toward the danger position, but only when such movement of the signal is caused by a train entering the section through which the signal governs traffic. For example, the circuit for the pick-up winding 34 of relay X³ is from the upper brush of motor 3 of signal S³ through wire 32, contact 6, back contact point 8, wire 36, contact 37 of track relay T⁶, back contact point 40, wire 38, pick-up winding 34, wires 19, 30 and 33 to lower brush of motor 3. It will be seen that this circuit is closed only when magnet 4 is deenergized and track relay T⁶ is open, hence the pick-up winding 34 is energized only when a westbound train enters section D—C. The current flowing in this circuit also retards the movement of the signal and thereby prevents shock to the signal mechanism when the danger position is reached. When signal S³ moves to danger position from any other cause, as, for example, when its controlling relay R³ is opened by an eastbound train entering stretch A—B, track relay T³ is closed, so that the circuit for motor 3 is then from the upper brush through wire 32, contact 6—8, wire 36, contact 37 of relay T³, front contact point 41, resistance 42, wires 30 and 33 to lower brush of motor 3. The current generated by the motor and flowing in this circuit also serves to retard the movement of the signal mechanism and to thereby prevent shock when the danger position is reached, the speed of such movement being determined by the value of resistance 42.

The holding winding 35 of each auxiliary relay is provided with a circuit which includes a front contact of the relay itself and a back contact of the corresponding signal relay. For example, the circuit for the holding winding 35 of relay X³ is from battery 10 through wires 11, 12, and 43, back contact 44 of signal relay R³, wire 45, contact 46 of relay X³, wire 47, holding winding 35, wire 48 and common wire 0 to battery 10.

Preferably the pick-up winding 34 and the holding winding 35 of each auxiliary relay are so arranged relative to each other that the flux in the relay core produced by the pick-up current in winding 34 is in the same direction as the flux produced by the holding current in winding 35.

The circuits for the pick-up and holding windings of auxiliary relays X⁵, X⁴ and X⁶ are similar to those just traced for relay X³. Since the motor 3 of signal S' is not employed to energize an auxiliary relay, this motor is provided with a retarding circuit which is not controlled by a track relay, and which is from the upper brush of the motor

through wire 32, contact 6—8, wire 49, resistance 42, wires 30 and 33 to lower brush of the motor. It is understood that the motor for signal S^2 is provided with a similar retarding circuit.

The operation of the apparatus during the passage of a westbound car or train through the stretch is as follows—as the car or train enters section B—D, it opens track relay T' , thereby opening at contact 20 the circuit for signal relay R' , which relay in turn opens at contact 51 the circuit for signal S^2 so that this signal then moves to danger. The opening of track relay T' also 10 opens at contact 50 the circuit for signal relay R^6 , which latter relay opens at contact 52 the circuit for signal S^6 so that this signal also moves to danger position. The opening of signal relay R^6 opens at contact 15 53 the circuit for signal relay R^4 , which latter causes signal S^4 to move to danger; relay R^4 in turn opens the circuit for relay R^2 thereby causing signal S^2 to move to danger position. It will be seen, therefore, that all 20 of the eastbound signals are now in danger position thereby prohibiting the passage of an eastbound car or train through the stretch A—B.

As the car or train passes out of sub-section B—56 and enters sub-section 56—D, it opens track relay T^6 and permits track relay T' to close, but this has no effect on the signals, because these two track relays control the same circuits.

As the car or train enters the sub-section D—57, it opens track relay T^3 , which latter opens at contact 54 the circuit for signal relay R^3 thereby opening at contact 28 the circuit for the holding magnet 4 of signal 35 S^3 so that this signal then moves to danger position. Track relay T^3 being open, the circuit for the pick-up winding 34 of auxiliary relay X^3 is closed so that this winding is energized by the current generated by 40 motor 3 of signal S^3 while this signal is moving toward danger position, and relay X^3 is thereby closed. Inasmuch as signal relay R^3 is open, the circuit for the holding winding 35 of relay X^3 is closed at contact 45 54, so that this relay continues to be energized after signal S^3 has reached the danger position. Signal relay R^3 is now ineffective to control signal relay R' , so that as soon as the rear end of the car or train has left section B—D signal relay R' closes, thereby 50 causing signal S^2 to change to clear position so that a following westbound car or train may then enter the stretch A—B.

As the car or train passes out of the first 55 sub-section to section D—C and enters the second sub-section, it opens track relay T^4 and permits track relay T^3 to close, but this change has no effect on the signals because the circuits controlled by these relays are the same.

The operation of the apparatus during the passage of the car or train through the remainder of the stretch is the same as that thus far described, hence it need not be traced further.

The operation of the apparatus during the passage of an eastbound car or train through the stretch is the same as that just described for the passage of a westbound car or train.

One important feature of the apparatus 70 shown in Fig. 1 is that after an auxiliary relay is once closed there is no interval during which it is deenergized, hence these relays need not be slow-acting; in other words, the pick-up and holding circuits for each 75 auxiliary relay are prepared for their functions before current is applied to them, and the holding circuit is not afterward changed until time for the relay to be deenergized. Another important feature is 80 that each auxiliary relay is not closed until the proper time for it to perform its function. Still another feature is that an auxiliary relay which allows a signal to be cleared can not be closed until the next signal 85 in advance moves to danger, because it is the movement of this latter signal which causes the relay to close.

Referring now to Fig. 2, the apparatus here shown is the same as that shown in 95 Fig. 1, except that the auxiliary relays, which I have here designated Y, each comprise only a single winding, which winding is employed both for pick-up and holding purposes. For the sake of simplicity I have 100 in Fig. 2 shown only the signals S^2 and S^6 , and the apparatus pertaining thereto. The circuits shown in Fig. 2 are the same as those shown in Fig. 1, except that in Fig. 2 the holding circuit for each auxiliary relay 105 is as follows: from battery 10 through wires 11, 12 and 43, contact 44 of relay R^3 , wire 45, resistance 55, contact 46 of relay Y^3 , wire 47, winding of relay Y^3 , wires 19, 30 and common wire 0 to battery 10.

It will be noted that after relay Y^3 is closed, a portion of the current from battery 10 will flow through motor 3, the branch in which this portion flows being from wire 47 through wire 38, contact 37, wire 36, contact 6, wire 32, motor 3, wires 33 and 30 to battery 10. If this portion of the current were of sufficient value it would retard the movement of the signal toward danger and might even stop the signal and drive 110 it back to clear position. The purpose of the resistance 55 is to limit the current from battery 10 to such value that the portion which flows through motor 3 will not interfere with the movement of the signal toward 115 danger.

With the structure shown in Fig. 2, the pick-up and the holding currents in each auxiliary relay Y are in opposite directions. The pick-up current, while it exists, is 120

stronger than the holding current, hence as the former dies away there is a reversal of the direction of current in the relay winding. Hence the auxiliary relays must be of a type which will not open when the direction of current in its winding reverses. Relays of this type are well known in the art. These relays may, for example, comprise three poles two only of which are provided with windings, the windings having different inductances.

Although I have herein shown and described only two forms of signaling system embodying my invention, it is understood that various changes and modifications may be made therein within the scope of the appended claims, without departing from the spirit and scope of my invention.

Having thus described my invention, what I claim is:

1. In combination, a stretch of railway track, signals located at intervals through the stretch for governing traffic in one direction, and other signals located at intervals through the stretch for governing traffic in the other direction; each signal comprising an electric motor arranged to be driven as a generator by the signal while the latter is moving toward danger, a signal relay for controlling each signal, track circuits for the stretch including track relays for controlling said signal relays, means for controlling each signal relay by the signal relay for the signal next in advance governing traffic in the same direction, an auxiliary relay for each signal for rendering the corresponding signal relay ineffective to control the signal relay for the signal next in the rear, and means for energizing each of said auxiliary relays by current generated by the motor of the corresponding signal while the latter is moving toward danger.
2. In combination, a stretch of railway track, signals located at intervals through the stretch for governing traffic in one direction, and other signals located at intervals through the stretch for governing traffic in the other direction; each signal comprising an electric motor arranged to be driven as a generator by the signal while the latter is moving toward danger, a signal relay for controlling each signal, track circuits for the stretch including track relays for controlling said signal relays, means for controlling each signal relay by the signal relay for the signal next in advance governing traffic in the same direction, and means for each signal and controlled by the current generated by the signal motor while the signal is moving toward danger for rendering the corresponding signal relay ineffective to control the signal relay for the signal next in the rear.
3. In combination, a stretch of railway track, signals located at intervals through

the stretch for governing traffic in one direction, and other signals located at intervals for governing traffic in the other direction, each signal comprising an electric motor arranged to be driven as a generator by the signal while the latter is moving toward danger, signal-controlling means for each signal, track circuits for the stretch including track relays for controlling said signal-controlling means, means for controlling each signal-controlling means by the signal-controlling means for the signal next in advance governing traffic in the same direction, and means for each signal and controlled by current generated by the signal motor while the signal is moving toward danger for rendering the corresponding signal-controlling means ineffective to control the signal-controlling means for the signal next in the rear.

4. In combination, a stretch of railway track, signals located at intervals through the stretch for governing traffic in one direction, and other signals located at intervals through the stretch for governing traffic in the other direction; each signal comprising an electric motor arranged to be driven as a generator by the signal while the latter is moving toward danger, a signal relay for controlling each signal, means for controlling each signal relay by the signal relay for the signal next in advance governing traffic in the same direction, an auxiliary relay for each signal for rendering the corresponding signal relay ineffective to control the signal relay for the signal next in the rear, a pick-up and a holding circuit for each auxiliary relay, each pick-up circuit including the motor of the corresponding signal and each holding circuit including a front contact of the auxiliary relay itself, and track circuits for the stretch including track relays for the control of the signal relays and of the circuits for the auxiliary relays.

5. In combination, a stretch of railway track divided into a plurality of sections, a pair of opposing signals located substantially at each junction of adjacent sections for governing traffic in opposite directions, each signal comprising an electric motor arranged to be driven as a generator by the signal while the latter is moving toward danger, a signal relay for the control of each signal, track circuits for the sections, each including a track relay for controlling the signal relay for each signal governing traffic through the section; means for controlling each signal relay by the signal relay for the signal next in advance governing traffic in the same direction, an auxiliary relay for each signal adapted when energized to render the corresponding signal relay ineffective to control the signal relay for the signal next in the rear, a pick-up

and a holding circuit for each auxiliary relay, each pick-up circuit including the motor of the corresponding signal and a back contact of a track relay for the section through 5 which the last-mentioned signal governs traffic, and each holding circuit including a front contact of the auxiliary relay and a back contact of the corresponding signal relay and a source of current.

10 6. In combination, a stretch of railway track, signals located at intervals through the stretch for governing traffic in one direction, and other signals located at intervals for governing traffic in the other direction, each signal comprising an electric motor for moving it toward clear position and said motor being operatively connected with the signal to be driven thereby as a generator when the signal is returning toward danger position, a signal relay for each signal, means for each signal and controlled by the corresponding signal relay for supplying current to the signal to drive it to the clear position and to hold it in 25 clear position, means for controlling each signal relay by the signal relay for the signal next in advance governing traffic in the same direction, an auxiliary relay for each signal for rendering the corresponding signal relay ineffective to control the signal relay for the signal next in the rear, means for energizing each auxiliary relay by current generated by the motor of the corresponding signal while the signal is moving 30 toward danger, and track circuits for the stretch including track relays for controlling said signal relays and said auxiliary relays.

35 7. In combination, a stretch of railway track, signals located at intervals through the stretch for governing traffic in one direction, and other signals located at intervals through the stretch for governing traffic in the other direction; each signal comprising an electric motor arranged to 40 be driven as a generator by the signal while the latter is moving toward danger, a signal relay for controlling each signal, means for controlling each signal relay by the signal relay for the signal next in advance governing traffic in the same direction, an auxiliary relay for each signal for rendering the corresponding signal relay ineffective to control the signal relay for the signal next in the rear, each auxiliary relay 45

55 comprising a pick-up winding and a holding winding, means for energizing the pick-up winding of each relay by current generated by the motor of the corresponding signal while the latter is moving toward danger, a stick circuit for the holding winding 60 of each auxiliary relay, and track circuits including track relays for controlling said signal relays and said auxiliary relays.

65 8. In combination, a stretch of railway track, signals located at intervals through the stretch for governing traffic in one direction, and other signals located at intervals for governing traffic in the other direction, each signal comprising an electric motor arranged to be driven as a generator 70 by the signal while the latter is moving toward danger, means controlled by a train in the stretch for causing all of the signals for the stretch to indicate danger, and means controlled by the current generated 75 by the signal motors for rendering said means ineffective to hold at danger the signals in the rear of the train governing traffic in the direction of movement of the train after the train has passed out of the 80 portion of the stretch governed by such signals.

85 9. In combination, a stretch of railway track, signals located at intervals through the stretch for governing traffic in one direction, each signal comprising an electric motor arranged to be driven as a generator by the signal while the latter is moving toward danger, a signal relay for controlling each signal, track circuits for the stretch including track relays for controlling said signal relays, means for controlling each signal relay by the signal relay for the signal next in advance, an auxiliary relay for each signal for rendering the corresponding signal 90 relay ineffective to control the signal relay for the signal next in the rear, and means for energizing each auxiliary relay by current generated by the motor of the corresponding signal while the latter is 95 moving toward danger.

100 In testimony whereof I affix my signature in presence of two witnesses.

SEBASTIAN C. HOFMANN.
